Inventor

By *Oliver A. Smith*
Attorney

Patented Oct. 6, 1925.

UNITED STATES PATENT OFFICE.

CLINTON ADAM LIVINGSTON, OF LONG BEACH, CALIFORNIA.

CHANGEABLE EXHIBITOR.

Application filed February 26, 1924. Serial No. 695,256.

To all whom it may concern:

Be it known that I, CLINTON ADAM LIVINGSTON, a citizen of the United States, residing at Long Beach, in the county of 5 Los Angeles and State of California, have invented certain new and useful Improvements in Changeable Exhibitors, of which the following is a specification.

This invention relates to the general art 10 of changeable exhibitors and has more specific reference to the form of changeable exhibitor known as the double reel and web type, the primary object of the invention residing in the provision of a changeable exhibitor that may be employed in dance 15 halls, theatres, auditoriums and the like for indicating to the public the next feature upon the program, or one that may be employed upon street cars or motor busses for 20 indicating the name of the approaching street, or the point at which the vehicle is next to be brought to a stop.

An additional object of the invention resides in the provision of such a changeable 25 exhibitor that may be manufactured and marketed at relatively small cost and one that may be employed in all of the instances set forth above, without requiring any material change to the general structure of 30 the device.

With the foregoing and other objects in view as the nature of the invention will be better understood, the same comprises the novel form, combination and arrangement 35 of parts hereinafter more fully described, shown in the accompanying drawing, and claimed.

In the drawing wherein like reference characters indicate corresponding parts 40 throughout the several views,

Figure 1 is a front elevational view of a changeable exhibitor constructed in accordance with the present invention,

Figure 2 is a view similar to Figure 1, 45 the cover plate being removed, and Figure 3 is a detail vertical sectional view taken substantially upon the line 3-3 of Figure 1.

Now having particular reference to the 50 drawing, my novel changeable exhibitor includes the provision of an open-sided sheet metal casing 5 of any desirable size or configuration.

Disposed for rotation within said casing 55 5, is a pair of superposed rolls 6-6, to

which are secured the opposite ends of a strip of fabric or other suitable material 7 of any desirable length upon which is to be horizontally printed certain indicating indicia such as the names of the next acts 60 appearing upon a theatre program, the names of dances to be played by the orchestra of a dance hall or auditorium, or the names of the streets or stops of cars, busses or the like, or the names of the points of 65 destination of said cars or busses, etc., etc.

Associated with adjacent ends of these rollers 6-6 are shafts or pintles 8-8 that extend outwardly of the adjacent end wall 70 of the casing 5 and are formed with squared portions for the reception of a crank handle 9 whereby the strip 7 may be wound in opposite directions.

Adapted to be detachably positioned upon the open side of the casing 5 is a sheet metal 75 cover or lid 10 that is formed adjacent its lower edge with a longitudinally extending opening 11 whereby the different indicating indicia upon said fabric strip 7 may be 80 readily viewed.

This lid 10 is formed at a point directly above said opening 11 with a longitudinally extending slide plate guide 12 that is provided with a relatively elongated opening 13 in its front side and adapted to be positioned within which is a strip of sheet metal 85 14 that is also formed with indicating indicia, such as "Next dance", "Next stop," or "Next act".

Summarizing the invention it is obvious 90 that I have evolved and produced a rectangular body which is open on one side, there being a pair of rollers journaled in this body with a legend carrying and display strip arranged to wind upon these 95 rollers. A cover is provided with a flange adapted to fit over the open side of the body, and this cover is provided with openings wherein the side edges are purposely located at equal distances beyond the opposite sides of the axes of the rollers when the cover is in position upon the body. The outer edges of the openings are thus spaced equal distances from the adjacent edges of the cover so that the cover may be reversed 100 in its position upon the body. This construction and arrangement is advantageous in that the legend upon the slide may be located at the upper or lower portion of the 105 body as desired, and when the slide is 110

located at the upper portion of the body, the legend thereon is read first, and the legend which appears upon the strip of flexible material is read following the legend 5 upon the slide. When the cover is reversed in its position upon the body, and the slide is located at the lower portion of the body, the legend upon the strip of material is read first through the upper opening in the 10 cover, and the legend upon the slide is read thereafter. In this way the legends may be interchanged by reversing the cover to cause the sign to read "Next dance—fox trot", or "Fox trot—next dance".

15 From the foregoing it will at once be evident that I have provided a highly novel, simple and useful form of changeable exhibitor and one that will meet with all of the requirements for a successful commercial use.

20 Minor changes may be made in the invention without departing from the spirit and scope of the appended claim.

Having thus described my invention, what

I claim as new, and desire to secure by 25 Letters Patent is:—

A changeable sign exhibitor comprising a rectangular body which is open at one side, a pair of rollers journaled in the end walls of the body, a legend carrying and display 30 strip arranged to wind upon the rollers, a cover having a flange adapted to fit over the open side of the body, the cover being provided with openings, the side edges of which are located at equal distances beyond the opposite sides of the axes of the rollers when the cover is in position upon the body, the outer edges of the openings being spaced at equal distance from the adjacent edges of the cover whereby the cover may be re- 40 versed in its position upon the body, the cover being provided with guides disposed along the edges of one of the openings, and a slide adapted to enter the guides and close 45 said opening.

In testimony whereof I affix my signature.

CLINTON ADAM LIVINGSTON.
